UNITED STATES PATENT OFFICE.

SISTA LOUISE DIXON, OF KANSAS CITY, MISSOURI.

DESIGN FOR A COMPARTMENT-PAN.

SPECIFICATION forming part of Design No. 33,218, dated September 18, 1900.

Application filed August 22, 1900. Serial No. 27,735. Term of patent 7 years.

To all whom it may concern:

Be it known that I, SISTA LOUISE DIXON, a citizen of the United States of America, residing in Kansas City, in the county of Jackson and State of Missouri, have invented and produced a new and original Design for Compartment-Pans, of which the following is a specification, reference being had to the accompanying drawings, forming a part thereof.

Figure 1 represents a plan view of a compartment-pan, showing my design. Fig. 2 represents a rear elevation view of the same. Fig. 3 represents a front elevation view. Fig. 4 represents a vertical sectional view taken on the dotted line *c d* of Fig. 1, indicated by the arrow *a*. Fig. 5 represents a side elevation view looking in the direction indicated by the arrow *b* in Fig. 1.

The leading or material feature of my design consists in the configuration of the pan. The bottom of the pan *A* is elliptical in form, with the exception of the near side, as viewed in Fig. 1. The form of this side is concave in the center, the ends of the arc of this portion and the two arcs at the end of the base being joined by straight lines. Extending upwardly from and around the entire periphery of the base *A* are the side walls of the pan. That portion of the pan indicated by *B* and comprising that portion of the side walls erected on the concave portion of the base is perpendicular to the base and is surmounted

upon its top by an inwardly-extending horizontal flange *C*. The pan is formed into three compartments by means of two vertical partitions *D*, having the same height as the rear wall *B*, and diverge from the inner convex side thereof forward to the front convex portion of the base *A*. The forward edges of the partitions *D* incline upwardly and forwardly from the forward edge of the base *A*. An inclined front wall *E* of the same height as the partitions *D* and joining the two outer ends thereof is curved concentrically with the forward side of the base *A*. The end walls *F* are vertically disposed with reference to the base *A*. These walls are not of the same height throughout, but descend from each end of the wall *B*, each in the form of an ogee, (indicated by *G*.) to a point where begins the round end of the base, from which point it continues at an even height clear to the partition *D*, where it joins the end of the wall *E*.

Having thus described my design, what I claim is—

The design of compartment-pan, substantially as herein shown and described.

In testimony whereof I have signed my name to this specification in the presence of two subscribing witnesses.

SISTA LOUISE DIXON.
